US00D934262S

(12) **United States Design Patent** (10) Patent No.: **US D934,262 S**
Manzano et al. (45) Date of Patent: **** Oct. 26, 2021**

(54) **CASE FOR PORTABLE ELECTRONIC COMPUTING DEVICE**

(71) Applicant: **Pioneer Square Brands, Inc.**, Seattle, WA (US)

(72) Inventors: **Megan Elizabeth Zumel Manzano**, Seattle, WA (US); **Jaimie Emerald Chan**, Renton, WA (US); **Brian Lewis Piper**, Seattle, WA (US)

(73) Assignee: **PIONEER SQUARE BRANDS, INC.**, McLean, VA (US)

(**) Term: **15 Years**

(21) Appl. No.: **29/770,105**

(22) Filed: **Feb. 9, 2021**

(51) LOC (13) Cl. **14-02**

(52) U.S. Cl. **D14/440**
USPC .....

(57) **CLAIM**

The ornamental design for a case for portable electronic computing device, as shown and described.

DESCRIPTION

FIG. 1 is a top perspective view of a case for portable electronic computing device showing our new design.

FIG. 2 is a front elevational view thereof.

FIG. 3 is a rear elevational view thereof.

FIG. 4 is a right elevational view thereof.

FIG. 5 is a left elevational view thereof.

FIG. 6 is a top plan view thereof; and,

FIG. 7 is a bottom plan view thereof.

The features shown in broken lines in the drawing figures depict features that form no part of the claimed design.

1 Claim, 7 Drawing Sheets
